CORPORATION OF NEW YORK

RADIO AMPLIFYING SYSTEM

Application filed May 7, 1923. Serial No. 637,063.

This invention relates to improvements in amplifying radio receiving systems.

An object of the invention is to obtain maximum amplification with minimum number 5 of thermionic tubes.

The invention resides in the methods and apparatus described below and shown in the drawings, of which

Figures 1 and 2 show a preferred embodiment, Fig. 1 being generally schematic to show the route taken by the currents through the system, and Fig. 2 being a complete diagram of the arrangement of the circuits and apparatus, all the individual pieces of apparatus being well-known in the art, i. e., the thermionic tubes (audions), batteries, the amplifier transformers, filter transformers, and the aerials, oscillator, rheostat, condensers, and telephones, all of which may be of 15 any of the well-known types and of values suitable for use with the particular tubes and frequencies involved in any particular design of receiving set employing the invention;

Fig. 3 is a general schematic drawing of a modified form which lacks certain features of the form of Figs. 1 and 2 which figures, however, illustrate the arrangement of circuits and apparatus for the embodiment of 25 Fig. 3.

Figs. 4 and 5 show another modification which employs less tubes, although a form found by me to constitute a practical embodiment of the invention; Fig. 4 being a schematic (as Fig. 1), and Fig. 5 being a complete working diagram (as Fig. 2).

Fig. 6 is a schematic drawing showing two radio frequency reflexes, i. e., three radio frequency amplifications by the same audion 40 tubes (and an audio frequency reflex), and illustrating the fact that the number of radio frequency reflexes is limited only by the upper limit of received radio frequency or 45 input from the aerial.

The invention is particularly useful in receiving radio communications having wavelengths of the order of a hundred meters or less, that is, frequencies of the order 50 of from, say several millions of cycles per

second down to one hundred thousand or less.

As shown in Fig. 1, there may be four amplifier tubes (1-4) more or even less, an oscillator tube 5 and a detector tube 6 (or 55 the functions of tubes 5 and 6 may be executed by a single tube as well known); filters F¹ and F² constructed to pass only one band of frequencies each; and a telephone or other receiver R, with a small wave-collector or aerial A. 60

In operation, the radio frequency currents first, upon reception, are amplified by tubes 1-4 prior to any detection (rectification); also, prior to any actual detection, currents 65 from oscillator 5 are added to the input or received radio frequency currents, the currents from tube 5 being of such frequency as will form radio frequency beats with said input currents, of lower frequency than the 70 latter, all as indicated in Fig. 1 by way of example. (The numerals on Fig. 1 represent frequencies.) As is well known in heterodyne or beats practice, the oscillator frequency may have any one of a large number 75 of values different from the input frequency, such as approximately the input frequency plus or minus the desired beat frequency, or half the input frequency plus or minus the desired beat frequency, or, say, one-third the 80 input frequency plus or minus the desired beat frequency, etc. The above route through the tube system is indicated by line X, i. e., the part of the system traversed by 85 the input radio frequency.

In detector tube 6 are rectified the mixed input and local oscillator frequencies, both of which are at radio frequency and which contain the radio frequency as a beat. From tube 6 along route Y pass the rectified radio 90 frequency beats; all other frequencies (including as yet unamplified audio frequencies which may pass through the other filter F²) being blocked by filter F from passage beyond detector 6 in this route Y. 95

Route Y takes the radio frequency beat current through amplifying tubes 1-4 back to detector 6, which now rectifies it, producing the audio frequency current originally 100 present in the input X as modulated at the

distant transmitter, for route Z to filter F² (Filter F² prevents a passage through route Z of radio beats which properly pass through filter F¹.)

Route Z now takes the audio frequency through amplifier tubes 1-4 and thence to R for observation or final receipt.

Oscillating tube 5 may add its currents to the input current at any point between aerial A and tube 6 inclusive (see Fig. 5).

The operation in general in the complete diagram of Fig. 2 is in general the same as in schematic Fig. 1, as above described.

In Fig. 2 are shown the filaments, grids and plates of tubes 1-6. The complete circuits are shown in Fig. 2, in lieu of the single lines or routes of Fig. 1 which there represent the two sides of each circuit. The filaments are connected by buses as usual to the A battery (BA) via filament rheostat H. Plate battery BB is shown as usual. The amplifier transformers between the tubes are illustrated by the usual conventions with their accessories including by-pass condensers. Those transformers which are in route X of Fig. 1 are marked in Fig. 2 X¹, X², X³, X⁴; those in route Y are marked Y¹-Y⁴ inclusive; and those in route Z Z¹-Z³ inclusive. Conductors in Fig. 2 which are traversed by the currents in routes X, Y and Z of Fig. 1 are likewise marked in Fig. 2. Detector tube 6 is shown as provided with the usual grid-leak GL and grid condenser GC. Oscillator tube 5 is shown as provided with the usual frequency determining elements FD, feed-back FB and mixer coil M, the latter in inductive relation to amplifier transformer X⁴ whereby the locally generated oscillations are supplied as in Fig. 1 to the input current just before rectification by detector tube 6; although, as stated in connection with Fig. 1, this supply may be to the input currents at any stage of their amplification or before they have been amplified at all, because there is not need of amplifying the locally generated oscillations because they may be generated with any desired amplitude. In Figs. 1-2 there are successively three amplifications by the same tubes, first at a high order of radio frequency (that of input X), second at a lower order of radio frequency (radio frequency beats), and third, at audio frequency.

In Fig. 3 is shown in the manner of Fig. 1 a modification which lacks audio frequency route Z of Figs. 1-2 through the amplifying tubes. From tube 4 in Fig. 3, the current previously first amplified by tubes 1-4, rectified by tube 6 and again amplified at reduced radio beat frequency by tubes 1-4, is rectified to audio frequency and led at Z directly to the indicator R, without, as in Figs. 1-2, being first further amplified (at audio frequency) by tubes 1-4. Otherwise the system of Fig. 3 is the same as

Figs. 1-2 in providing two successive radio frequency amplifications by the same tubes, and its embodiment in detail is the same as in Fig. 2, save for the omission of the circuits and apparatus of Fig. 2 corresponding to the Z amplifying route at audio frequency of Fig. 1.

In Figs. 4 and 5 is shown a system like that of Figs. 1-2 in having radio and audio reflexes or routes X and Y through the amplifier and the detector; but a solid rectifier or "crystal" detector 6 is shown in lieu of the audion detector 6 of Figs. 1-3, and only one amplifier (a tube 1) is shown in lieu of the four amplifier tubes 1-4 of Figs. 1-3. The oscillator 5 may be a tube as in Figs. 1-3. In Figs. 4-5, the oscillator 5 is shown as having its current mixed with the input X prior to any amplification of the input, i. e., the oscillator is connected to the input circuit in advance of amplifier 1, instead of being connected to the detector 6 as in Figs. 1-3.

In general, the operation of Figs. 4-5 is like that above-disclosed of Fig. 1. With any form of the present invention, a small aerial may be used, or a minimum number of tubes, or both.

The details of Fig. 5 (the complete diagram for the scheme of Fig. 4) are similar to the details of Fig. 2 (the diagram of the scheme of Fig. 1). In Fig. 5, where the oscillator 5 is coupled to the input prior to any amplification, the mixing coil M may be, as shown, the secondary of a transformer of which the primary is the entire loop aerial A itself, coil L being mounted to be rotatable with loop aerial A. Of course, grounded antennae may be used in lieu of the loop aerial in all cases.

In the diagram, Fig. 5, transformer X¹ passes the amplified currents of route X from the plate circuit of tube 1 to detector 6. Also transformer Y¹ passes the amplified Y currents from the plate circuit of tube 1 to detector 6. A grid battery GB is inserted in the grid-filament circuit of the tube.

In Fig. 5 oscillator 5 supplies to input X and detector 6 a radio frequency current of plus or minus 360 meters, as indicated in Fig. 5, i. e., such a radio frequency as will produce (with input X) a radio frequency beat. This beat is rectified by "crystal" detector 6 and is passed through filter F¹ which is constructed to pass only the resultant beat frequency (5,000 meters indicated in Fig. 5) to route Y (Figs. 4 and 5). This beat frequency in route Y then is amplified by tube 1 and passed again to detector 6 where it is again rectified. The product of this second rectification is audio frequency current passing in the Z route. This audio frequency then is amplified by tube 1 and passed directly to indicator R.

In Fig. 6 is shown by schematic drawing a form of the invention in which, the input

frequency being sufficiently high (as in present-day broadcasting with short waves), i. e., 100 meters (3,000,000 cycles per second), there are two radio reflexes through the two amplifying tubes 1 and 2, and the detector tube 6 (i. e., three successive radio frequency amplifications by the same tubes, each amplification being followed by a rectification by tube 6 and a consequent reduction of degree of frequency; the third or last rectification resulting in audio frequency Z). This is one more radio frequency amplification by the same tubes than in Figs. 1-5.

Before the first of the two reflexes, (second radio frequency amplification), oscillator tube 5 supplies frequency U at the value noted on the drawing (i. e., the input frequency in aerial A plus or minus the desired higher radio beat frequency of 200,000). The rectified mixture of input and oscillator frequencies passes from rectifier tube 6 via filter F¹ and route X to the two amplifying tubes 1-2 for the second radio frequency amplification. For the second reflex (third radio frequency amplification) oscillator 5 supplies frequency V at the value noted on the drawing (i. e., the first beat frequency of 200,000 plus or minus the desired higher radio beat frequency of 30,000). Route Y via filter F² then takes the rectified product of such amplification (at the lower beat frequency) to tubes 1-2, the third radio frequency for amplification. (Such lower beat frequency is the result of the mixture of the first or higher beat frequency with the V frequency of oscillator 5.) Route Z via filter F³ finally takes the rectified product of such amplification, in the form of audio frequency, to tubes 1-1 for final or audio frequency amplification, whence such currents pass to indicator R for observation.

The advantages of the invention include the following.

The amplification of the radio frequency input prior to detection and the mixture of the locally generated oscillations with the input prior to detection cause greatly increased amplifying efficiency because, as the operation of detection obeys an input-voltage square-law, the detector output of beat current is thereby enormously increased by such amplification in combination with such heterodyning prior to detection. By this means is greatly extended the practical limits heretofore existing to amplification by heterodyning and even super-heterodyning. To the end of obtaining maximum amplification with minimum tubes, the above result in enhanced greatly by the described reflexing once (two radio frequency amplifications by the same tubes), twice (three radio frequency amplifications by the same tubes), or even more times, of the beats at successively lower degrees of radio frequency, all of which amplification is finally enhanced by the recti-

fication of the final product of the last amplification of the radio frequency beats and the final reflexing of such audio frequency product before observation by the receiving phones. Greatly exceeding any amplification heretofore possible is that obtained by the use of the same tubes in this invention for amplifying at radio frequency several successive times, i. e., at successively lower radio beat frequencies, by successive heterodyning at radio frequency. As appears hereinbefore, it is the reduction from higher to lower radio frequency by the beats operation which permits reamplification at radio frequency by the same tubes. The beats operation, therefore, serves as a means which permits successive amplifications at radio frequency by the same tubes, without passing the currents through the same tubes at the same degree of radio frequency.

Also, while heterodyning to produce audio frequency is not practicable with radiophoning, yet the invention lends itself readily to such heterodyning for radio telegraphy; all that is necessary being the supply from oscillator 5 in any of the figures hereof, of an additional radio frequency of such value as will produce an audio frequency beat note with the last or lowest radio frequency beat in the system, such value being for example, in the case of Fig. 6, 30,000 cycles plus or minus the frequency of the desired audible beat note such as 500 to 1,000 cycles per second, corresponding with the musical note for telegraphic dots and dashes as in the ordinary heterodyne of the prior art.

Herein, as in all systems of high amplification, it is essential to avoid, so far as possible, all feed-backs which would produce undesirable oscillations. No set rule can be laid down for the exact disposition of the apparatus and leads; but when such undesirable oscillations are found to occur, they may be stopped by changing the poling or direction of connection in circuit of the windings of the transformers and filters. Also, the various parts of the apparatus, especially the transformers, may be changed in relative location until such oscillations thereby are stopped. Also, as a substantial portion of the undesirable feed-backs occur between leads connecting various elements of the apparatus, the relative positions of such leads may be altered as a means for stopping such oscillations. Again, such undesirable oscillations may be stopped by counteracting the displacement currents from plate to grid (which are a prolific cause of such oscillations), as in any of the well-known ways, such, for example, as that shown in United States patent to Rice No. 1,334,118.

While the best amplification is obtained by the forms of reflexing shown and described, yet the invention involving radio frequency amplification and heterodyning detection is

extremely useful without any such reflexing, in which case the product of the first rectification of amplified and heterodyned input is led direct to receiving telephone R, in any of the figures. The reflexing of the radio beat frequency (all figures) is especially advantageous, however, not merely in extent of amplification, but in the freedom of distortion as compared with audio frequency reflexing, due to the fact that such beats, being at radio frequency and covering only a narrow frequency band, can be re-amplified, and repeatedly amplified, by the same tubes, at successively reduced radio beat frequencies, without resulting distortion such as occurs with the reflexing of audio frequencies covering a wide band. In this connection, the constructor is advised to obtain desired higher amplification in the use of the invention rather by reflexing (re-amplification) of radio frequency beats (Figs. 1-5) and by repeated reflexing of the radio frequency beats (Fig. 6) than by audio frequency reflexing, although the latter also may be used advantageously if not to excess; and at times audio frequency reflexing may be employed over a fraction of the succession of amplifying tubes if not over all of those employed for radio frequency amplification. A further specific illustration of a preferred form of the invention, constructed along the lines of the drawings, is one employing four amplifying tubes (as in Fig. 1), all being connected to amplify the radio frequency input, (as in Fig. 1), but tubes numbers 2-4 inclusive being constructed for reflex amplification of radio frequency beats, and tubes numbers 3-4 inclusive being connected for reflex amplification of audio frequency. For I have found that, as the frequency is made lower in successive reflex stages, the stability of the train of amplifier tubes is decreased, so that it becomes advantageous in maintaining stability of the tubes in use at a given stage, to reduce their number as in the above illustration.

I claim:

1. The method of radio amplification by thermionic amplifying means, which consists, prior to detection, in amplifying received radio frequency currents at their radio frequency by such means and mixing with said radio frequency currents a locally generated frequency causing the production of radio frequency beats, then rectifying such radio frequency beats; and prior to observation, passing the rectified product through more or less of the same said amplifying means.

2. The method of radio amplification by thermionic amplifying means, which consists, prior to detection, in amplifying received radio frequency currents at their radio frequency by such means and mixing with said radio frequency currents a locally generated frequency causing the production of radio

frequency beats; then rectifying such radio frequency beats; then prior to a second rectification, passing said rectified product through more or less of the same said amplifying means and mixing with said rectified product a locally-generated frequency causing production of beats of a lower order of radio frequency than the first above beats; and prior to observation, passing the rectified product through more or less of the same said amplifying means.

3. The method of radio amplification by thermionic amplifying means, which consists in amplifying received radio frequency currents at their radio frequency by such means prior to detection and mixing with them a locally generated heterodyning frequency causing the production of radio frequency beats also prior to detection; then rectifying such radio frequency beats; then prior to a second rectification, passing said rectified product through more or less of the same said amplifying means; rectifying said amplified radio frequency currents to audio frequency; and, prior to observation, passing said audio frequency currents through more or less of the same said amplifying means.

4. The method of radio amplification by thermionic amplifying means, which consists, prior to detection, in amplifying received radio frequency currents at their radio frequency by such means and mixing them with a locally generated heterodyning frequency; subsequently changing to audio frequency and passing the audio frequency currents through more or less of the same said amplifying means.

5. The method of radio amplification by thermionic amplifying means, which consists prior to detection in amplifying received radio frequency currents at their radio frequency by such means and mixing with them a locally generated heterodyning frequency causing the production of beats; filtering out all currents save those of such beats; and, before observation, passing such beats through more or less of the same said amplifying means.

6. A thermionic tube amplifier, which comprises thermionic amplifying means connected to amplify the received currents at radio frequency; means for mixing heterodyning currents with the received currents prior to rectification; means for rectifying the resulting beats; means for filtering out all currents save those of the beats; and connections from the filtering means to more or less of the same said thermionic amplifying means to cause amplification of the beats.

7. A thermionic tube amplifier, which comprises thermionic amplifying means connected to amplify the received currents at radio frequency; means for mixing heterodyning currents with the received currents prior to rectification; means for rectifying the

beats; means for passing the resulting beats through more or less of said thermionic amplifying means and through said rectifying means; means for passing the resulting currents one or more additional times through more or less of said thermionic amplifying means; and a plurality of filtering means each located in one of the paths from the rectifying means to the thermionic amplifying means.

8. The method of amplifying radio frequency currents which consists in passing them thru a thermionic amplifying system and reducing them to a lower degree of radio frequency; passing such reduced radio frequency currents thru a greater or less extent of the same said amplifying system and reducing the frequency to audio frequency; and passing such audio frequency currents thru a greater or less extent of the same said amplifying system.

9. A thermionic tube amplifier, which comprises thermionic amplifying means connected to amplify received radio currents at their received radio frequency; means for reducing the frequency to a lower degree of radio frequency; means for passing the lower radio frequency currents thru a greater or less extent of the same said amplifying means; and means for filtering currents of other frequencies from the path of the lower radio frequency currents to said amplifying means.

10. The method of amplifying radio frequency currents, which consists in passing them at radio frequency thru a thermionic amplifying system and also forming the radio frequency currents into radio frequency beats, both prior to detection; subsequently changing the radio frequency beats to audio frequency currents; passing the audio frequency currents thru a greater or less extent of the same said amplifying system; and finally observing the amplified audio frequency currents.

11. The method of amplifying radio frequency currents, which consists in passing them thru a thermionic amplifying system and reducing the frequency to a lower degree of radio frequency of amplified current; passing the reduced radio frequency amplified current thru a greater or less extent of the same said amplifying system while blocking currents of other frequencies from their path from frequency change to such amplification; subsequently changing the frequency to audio frequency; and passing said audio frequency currents thru a greater or less extent of the same said amplifying system while blocking currents of other frequencies from the path from frequency change to such amplification.

12. The method of amplifying radio frequency currents, which consists in passing them at their input radio frequency thru a thermionic amplifying system; heterodyning them at the same frequency and rectifying the

resulting radio frequency beats, producing a lower degree of radio frequency currents; and passing the reduced radio frequency amplified currents thru a greater or less extent of the same said amplifying system while blocking currents of other frequencies from their path between rectification and amplification.

13. The method of amplifying radio frequency currents, which consists in passing them thru a thermionic amplifying system at their radio frequency and in heterodyning them at said frequency, both prior to detection; then passing them thru a detector tube; subsequently passing the currents of reduced frequency thru a greater or less extent of the same said amplifying system; and finally passing the currents thru the same said detector tube and observing the resulting currents.

14. The method of amplifying radio frequency currents, which consists in passing them at radio frequency thru a thermionic amplifying system and in heterodyning them at the same frequency, both prior to detection; and then passing them thru a detector tube, reducing them to a lower degree of radio frequency, then passing the currents of reduced radio frequency thru a greater or less extent of the same said amplifying system; and then passing said amplified currents thru the same said detector tube.

15. The method of re-amplifying radio frequency currents by successive passages thru the same thermionic amplifying tube, which consists in heterodyning such currents by other radio frequency currents intermediate of such successive passages thru the tube, forming radio frequency beats which are amplified by the subsequent passage thru the tube.

16. An amplifying system in which the energy to be amplified is passed through the amplifier successively a number of times, comprising an amplifier, a plurality of re-entrant connections from the output of said amplifier to its input, each connection being arranged to pass a different frequency, and means associated with said amplifier to change the frequency of the energy each time it passes through the amplifier, each change corresponding to the frequency passed by a different one of said re-entrant connections.

GREENLEAF WHITTIER PICKARD.
